UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC SWITCH.

1,136,240.

Specification of Letters Patent. Patented Apr. 20, 1915.

Application filed August 26, 1912. Serial No. 717,066.

To all whom it may concern:

Be it known that I, CHARLES J. KLEIN, a citizen of the United States, residing at Milwaukee, in the county of Milwaukee and State of Wisconsin, have invented new and useful Improvements in Electric Switches, of which the following is a full, clear, concise, and exact description, reference being had to the accompanying drawing, forming a part of this specification.

My invention relates to electric switches.

It has among its objects to provide an improved switch which is readily adapted to use in connection with the electric lamp sockets or other electric switch receptacles.

A further object of my invention is to provide an improved switch base and an improved arrangement and construction of conducting and terminal connections thereon, whereby the device may be made exceedingly compact, the parts are effectually insulated from each other and the switch terminals are readily accessible.

Other objects and advantages of my improved construction will hereinafter appear.

In order that my invention may be fully and clearly disclosed, I have illustrated one embodiment of the same in the accompanying drawings. It is to be understood, however, that the construction shown is susceptible of modification.

Figure 1 is a central sectional view of a lamp socket with my improved switch device in position therein. Fig. 2 is a vertical sectional view of the switch removed from the socket. Fig. 3 is a transverse sectional view on line 3—3 of Fig. 1. Fig. 4 is a side elevation of a construction shown in Fig. 2. Fig. 5 is a side elevation of the opposite side of the switch base shown in Fig. 4, the threaded shell being removed. Fig. 6 is a bottom view of the switch base. Fig. 7 is a transverse sectional view on line 7—7 of Fig. 2, the switch being removed. Fig. 8 is a perspective view of the movable contact member of the switch mechanism.

The insulating base housing the switch mechanism and carrying the terminal connections therefor is divided vertically into two parts 1 and 2 whose inner adjacent surfaces are provided with irregular shaped recesses 3 and 4. In these recesses the switch mechanism is housed and substantially sealed by the connection of the two parts to

each other through a U shaped member 5 and the screws 6 and 7 engaging therewith. The base is of substantially oblong or rectangular cross section (Fig. 3) and provided with flat sides upon which the binding posts 8 and 9 are mounted upon terminal plates 10 and 11. To support the base within a lamp shell 12 or other receptacle oppositely extending angular lugs or extension 13 are provided on the opposite sides of the same and at the upper end thereof.

The switch mechanism illustrated is of the push button type and of the same general construction as that described and claimed in my co-pending application Serial No. 623,903 filed April 28, 1911. This switch mechanism includes a reciprocable push button 14, cams 15 moving therewith and a movable contact member 16 pivoted upon a spindle 17 and actuated by said cams to compress a spring 18. At a predetermined position in the movement of the cams, this contact member is rotated with a quick snap action to make or break the circuit at resilient stationary contacts 19 and 20.

The construction of the switch shown herein, however, differs specifically from that shown in the aforesaid application. In this construction the movable contact member 16 is formed of a single piece of stamped metal having overturned contact surfaces 21 at its ends extending substantially at right angles to the body of the contact. At points between its pivot point and each of the contact surfaces 21, knob or nipple-like protuberances or bearing surfaces 22 are punched out of the body of the blank as shown in detail in Fig. 8. Further, the stationary contacts are of a different construction. The upper stationary contact 19 is provided with a flat base 23, having an extension 24 substantially at right angles thereto, to which is secured the resilient contact 19. This contact lies in a plane parallel with the plane of the rigid base. The contact 20 is shown in Figs. 1 and 7. In this instance the lower end of the contact is fixed to the bottom of the U shaped member 5 and is provided with a cut away portion 25, so that it may pass around the end of a screw 26, hereinafter referred to, and have increased resiliency. Both of these contacts are formed of light resilient metal and are fixed to their bases by any suitable

means, such for instance as riveting. In order to improve the contact and to give an arc shape to the active surface of the contact these contacts are slightly crimped or bent 5 along vertical lines 27, as illustrated in Fig. 1.

The stationary contact 19 is held in position by a screw 28, which extends through the base and serves as a means for fixing the 10 terminal plate 10 upon one side of the same. The screw 26, heretofore referred to, is received in a lug 29 on the bottom of the U-shaped member 5 and extends downward through the base at one side of the same and 15 with a companion screw 30 upon the opposite side of the base serves to clamp a plate 31 upon the upper overturned ends 32 of the threaded lamp shell 33. In Fig. 1 the inner end of the screw 30 is shown threaded into 20 a cup shaped nut 34 carried in correspondingly shaped recesses 35 in the adjacent walls of the base. The center contact 36 for the lamp or other device inserted within the threaded shell 33 is formed integral with the 25 terminal plate 10 and extends through a suitable opening or cut away portion 37 at the upper end of the threaded shell. As shown in Fig. 6 a disk-like projection 38 upon the bottom of the base is located above 30 the contact 36 and between the screws 26 and 30.

Assuming that suitable electrical connections are made to the binding posts 8 and 9 and that the switch is in open circuit position, as shown in Fig. 1, the circuit is closed when the push button is pushed to the right. Assuming that the current enters through the binding post 9, the circuit connections are then as follows: from the binding post 40 9, through the screw 28 to the stationary contact 19, through the movable contact 16, the stationary contact 20, the threaded shell 33, the device therein, and the center contact 36 to the binding post 8.

When it is desired to remove the switch mechanism from the socket or other suitable receptacle, it is only necessary to force the base upward to disengage the supporting lugs 13 from their supports in the walls of 50 the receptacle. To gain access to the switch mechanism it is only necessary to remove one of the screws 6, 7. By locating the binding posts upon the sides of the base, the same are rendered readily accessible and a substantial seat is provided for the same. If desired, suitable slanting conductor grooves 39 may be provided in the upper end of the base, which communicate with the binding posts (Fig. 3). These binding 55 posts while directly connected to the switch mechanism are spaced therefrom by a solid wall of insulation. The construction is exceedingly compact and may be readily and cheaply manufactured.

60 While I have herein specifically described

this one embodiment of my invention, it is to be understood that the form shown herein is susceptible of modification.

What I claim as new and desire to secure by Letters Patent of the United States is: 70

1. In combination, a casing, a two-part base having projections adjacent one end for supporting the same within said casing, the adjacent faces of the parts of said base having complementary recesses in the plane of 75 said projections, and a switch mechanism mounted in said recesses, the operating member of said switch mechanism extending through opposite walls of said base.

2. In combination, an elongated insulating base having flat sides, a switch mechanism housed therein, stationary contacts therefor, members fixing said contacts to the base and extending through the latter to the exterior thereof, terminal plates on the flat 80 sides of said base, one of said plates being fixed thereto by one of said members, and a threaded shell removably secured by the other member.

3. In combination, a switch base vertically divided into two sections, a snap switch mechanism inclosed between the sections of 85 said base, stationary contacts therefor carried by one of the parts of said base, screws for fixing said contacts to said base, a 90 threaded shell secured to said base by one of said screws, terminal plates carried on opposite sides of said base, one of said terminal plates being secured thereto by one of said screws and the other of said terminal plates 95 being provided with an extension forming a center contact protruding into said shell. 100

4. In combination, a two-part vertically divided base having flat sides, a substantially U-shaped member holding the parts thereof together, a snap switch mechanism carried between said parts, stationary contacts for such switch mechanism, a terminal plate carried upon one of the flat sides of the bases, means for directly connecting one of 105 said contacts with said terminal plate, a threaded shell, means for directly connecting said shell with the other of said contacts, and a combined center contact and a terminal plate, said center contact extending into 110 said shell and said terminal plate being carried upon the other flat side of the base. 115

5. In combination, a vertically divided two-part base having flat vertical sides, a snap switch mechanism housed between the parts of said base, means for holding the parts of said base together, stationary contacts carried by one of the parts of said base, screws for securing said stationary contacts to said base, said screws protruding through 120 the walls of said base, a threaded shell directly connected to one of said protruding screws, a terminal plate held in position upon one of the flat sides of said base by the other of said screws and a second terminal 125 130

plate fixed upon the opposite flat side of the base and having an elongated substantially L-shaped extension forming a center contact protruding within said shell.

5 6. A contact member having a contact surface at its end, and a punched out knob-like bearing surface between its ends.

7. A contact member having a body portion and contact portions at right angles thereto and a punched out bearing surface

in said body portion adjacent each of said contact portions.

In witness whereof, I have hereunto subscribed my name in the presence of two witnesses.

CHARLES J. KLEIN.
